UNITED STATES PATENT OFFICE.

DAVID C. BOYD, OF GALION, OHIO, ASSIGNOR TO THE GALION IRON WORKS AND MANUFACTURING COMPANY, OF GALION, OHIO, A CORPORATION OF OHIO.

SCARIFIER.

1,093,104.

Specification of Letters Patent. Patented Apr. 14, 1914.

Application filed March 24, 1913. Serial No. 756,539.

To all whom it may concern:

Be it known that I, DAVID C. BOYD, a citizen of the United States, residing at Galion, in the county of Crawford and State of Ohio, have invented certain new and useful Improvements in Scarifiers, of which the following is a specification.

This invention comprehends certain new and useful improvements in road machinery for use in making and repairing roads and relates particularly to what are known as scarifiers.

The invention has for its primary object a simple, strong and durable scarifier, the parts of which are so constructed and arranged that they will operate efficiently in breaking or cutting up the surface of a road to be repaired, which will be capable of withstanding to a maximum degree, the hard service which a road building machine is called upon to perform and will dig firmly into the material and effectively break the same up, no matter how hard the road may become and which will embody a novel arrangement of reversible teeth and a novel arrangement of parts for holding said teeth in position, whereby the teeth may be reversed end for end whenever desired, their serviceability being thereby enhanced.

The invention also has for one of its main objects an apparatus of this character which may be easily secured to the supporting frame-work of a road grader or scraper in lieu of the scraping blade and its supporting circle and draw bars whereby a combination machine may be produced, the machine, from a practical standpoint, thereby possessing this additional advantage of susceptibility of being changed from a scarifier to a grader or vice versa.

A still further object of the invention is the provision of an improved scarifier embodying two series of forwardly converging teeth, with a single tooth at the apex or forward end of the frame, common to both series, said tooth being preferably somewhat larger than the other teeth and being designed to first enter the material and break it away, the rear teeth on each side following after in regular succession, the side pressure being equalized and the scarifier thereby following the lead after the front tooth which, in turn, as is manifest, will follow the line of draft. And the invention also aims to generally improve devices of

this character so as to render them more useful and commercially desirable.

With these and other objects in view, as will more fully appear as the description proceeds, the invention consists in certain constructions, arrangements and combinations of the parts that I shall hereinafter fully describe and claim.

For a full understanding of the invention, reference is to be had to the following description and accompanying drawings, in which—

Figure 1 is a side elevation of a scarifier embodying the improvements of my invention. Fig. 2 is a sectional side elevation through one side of the main frame of the device. Fig. 3 is a transverse sectional view through one side of the frame. Fig. 4 is a horizontal sectional view therethrough. Fig. 5 is a horizontal sectional view, one section being taken on a plane passing underneath the tooth-retaining bars herein-after described and the other plane lying above said bars, and, Fig. 6 is a fragmentary longitudinal section on an enlarged scale.

Corresponding and like parts are referred to in the following description and designated in the accompanying drawings by like reference characters.

Referring to the drawings, A designates as a whole, the main frame of my improved scarifier, the sides of said frame converging in a forward direction and each consisting of a pair of preferably channeled bars 1 disposed in laterally spaced relation to each other with their flanges projecting outwardly, as clearly illustrated in Fig. 3. Teeth or blades 2 of any desired number are disposed at any predetermined intervals 95 between the channeled bars 1 of the sides of the main frame-work, said teeth, as will clearly be understood, being thus arranged in two forwardly converging corresponding series with a single tooth at the front, common to both series. Preferably, the foremost tooth is larger than the others and is set squarely in the front end of the scarifier frame. It is received in an upwardly and rearwardly inclined opening formed for it 100 in a substantially V-shaped casting or block 3 secured in between the channeled bars 1 at the extreme front end thereof, transverse bolts 4 passing through the bars and through said block and one of said bolts extending 110

transversely through the foremost tooth itself at the middle of the latter. Thus, it will be seen that this tooth is firmly held in position. It is to be particularly noted that 5 the other teeth are devoid of bolt holes. They are engaged on their front and rear edges by the adjacent edges of blocks 5 that are received in between the frame bars 1 and interposed between the teeth, as clearly 10 illustrated in Fig. 5, said blocks 5 being formed on said adjoining edges with beveled or wedge-shaped lip extensions 6 designed to engage, with their oblique edges, the side faces of the teeth, whereby the teeth 15 will be securely clamped between these beveled lips and always stand straight with the line of draft. It will be seen that the blocks 5, like the block 3, are formed in their side faces with recesses 7, in which the 20 channeled brace bars 1 fit, transverse bolts 8 passing through the frame bars and through the blocks 5 so as to produce a strong and rigid structure.

The teeth project upwardly above the 25 frame bars 1 and are provided with cutting and digging edges on both ends, whereby they may be reversed when required and the serviceability of the machine thereby increased to a marked degree.

30 Coöoperating with the blocks for the purpose of securely holding the teeth in position and for directly retaining the teeth or to prevent them from slipping upward and out of position, I have provided retaining bars 9 which, in the present instance, are of 35 channel formation with their flanges projecting upward, said retaining bars contacting with the upwardly disposed extremities of the teeth, as clearly illustrated in the 40 drawings, and being secured in position by tie bolts 10 arranged in transversely disposed pairs and disposed at any desired intervals along the bars 9, said tie bolts preferably extending through pipe ferrules or 45 bushings 11 which are used freely for the purpose of properly spacing the tooth-retaining bars from the main frame-work and for properly holding said retaining bars to the bars 1 in an evident manner.

50 In order to support the frame-work A in its operative position, I have provided the draw bars 12 which are connected to the main frame bars 1 and tooth-retaining bars 9 by bolts 13 which pass therethrough and 55 through transversely extending I-beams 14 which are interposed between the draw bars and the tooth-retaining bars. In the present embodiment of the invention, there are two of these I-beams employed, although it is to 60 be understood that the invention is not limited in this regard, and the draw bars 12 are connected near their forward ends to brace bars 15, the lower ends of which are 65 connected to a V-shaped block or casting 16 bolted to the tooth retaining bars 9 at the for-

ward extremities of the latter where they come together. The draw bars 12 are provided at their forward ends with a clevis 17, whereby they may be conveniently connected to the traveling frame-work or draft mechanism, and the rear ends of said draw bars are, in the present instance, provided with clips or stirrups 18 so that they may be easily secured to suspension link rods and the entire scarifier frame with its component parts held in the required position, vertically considered, at the will of the operator, according to the particular work in hand and how deep it is desired the teeth shall cut.

80 From the foregoing description in connection with the accompanying drawings, the operation of my improved scarifier will be apparent. In the practical use of the device, it is connected to the traveling frame-work 85 of the machine, for example, in lieu of the ordinary draw bars, scraper blade and circle, and it is adjusted vertically according to the requirements of the case, whereby as the machine is drawn forward by a traction engine or otherwise, the large front tooth will 90 enter the material and break it away. The rear teeth on each side will follow after in regular succession and on account of there being a row or series of teeth on each side, 95 the side pressure will be equalized and the scarifier will follow the lead from the front tooth which, as is evident, will follow the line of draft. It will be noted that with the exception of the foremost tooth, there 100 are no bolt holes through the teeth to weaken them, that they are held firmly in position by means which may be cheaply and easily manufactured and readily assembled and that they may be easily reversed 105 whenever desired.

110 While the accompanying drawings illustrate what I believe to be the preferred embodiment of my invention, it is to be understood that the invention is not limited thereto, but that various changes may be made in the construction, arrangement and proportions of the parts without departing from the scope of the invention, as defined in the appended claims. It is also to be understood that while my invention is primarily 115 designed for use in connection with that well known type of road machine which embodies a wheeled frame-work with means for raising and lowering the front end of draw bars, with means for laterally shifting the draw bars, and with means for raising one draw bar higher than the other, as required, and is also primarily designed for use in a combination road machine in substitution for the ordinary draw bars and scraping blade and circle connected thereto, yet, the invention is not limited in this regard, as it is clearly within the purview of my invention to employ any form or type 120 125 130

of traveling frame-work or draft device for operating my improved scarifier.

What I claim is:—

1. A road scarifier, including a frame-work, embodying sides consisting of laterally spaced bars, teeth disposed between said bars, blocks interposed between said bars and connected thereto and spacing said teeth from each other, and teeth-retaining bars connected to said frame-work and serving to prevent the upward displacement of said teeth.

15 2. A road scarifier, including a frame-work embodying side bars, a plurality of teeth mounted between said side bars and projecting both below and above the latter, tooth-retaining bars mounted above the said bars and engaging the upper ends of the teeth, and tie bolts connecting said tooth-retaining bars to the side bars.

25 3. A road scarifier, including a frame-work, embodying sides which consist of bars disposed in laterally spaced relation to each other, teeth interposed between said bars, and blocks disposed between said bars and between the teeth, said blocks being formed on their adjoining edges with lips engaging the sides of said teeth and holding the latter in oblique position relative to the bars.

30 4. A road scarifier, including a frame-work, the sides of which consist of laterally spaced bars, teeth disposed between said bars, and blocks arranged between said bars

and interposed between the teeth, said blocks being formed on their adjoining edges with 35 beveled lips adapted to engage the side faces of the teeth so as to hold the latter in oblique position relative to the length of the side bars.

5. A road scarifier, including a frame-work, teeth carried by said frame-work and projecting above the same, tooth-retaining bars engaging the upper ends of the teeth and connected to the frame-work, draw bars above said tooth-retaining bars, and transverse beams connected to the tooth-retaining bars and the draw bars.

40 6. A road scarifier, including a frame-work provided with tooth-retaining bars, teeth carried by said frame-work and projecting above the same and engaging with their upper ends the lower faces of the tooth-retaining bars, transversely extending beams connected to the tooth-retaining bars, and 45 draw bars connected to the transverse beams, 50 said draw bars being provided at their forward ends with a clevis and at their rear ends with stirrups, as and for the purpose set forth.

55 In testimony whereof I affix my signature 60 in presence of two witnesses.

DAVID C. BOYD.
